UNITED STATES PATENT OFFICE

GEORGE H. PACKWOOD, JR., OF ST. LOUIS, MISSOURI, ASSIGNOR TO G. H. PACKWOOD MFG. COMPANY, OF ST. LOUIS, MISSOURI, A CORPORATION OF MISSOURI

REGULATABLE DISCHARGE MEANS FOR SOAP DISPENSERS

Application filed February 26, 1929. Serial No. 342,827.

This invention relates to commodity dispensers and particularly to devices for dispensing powdered or liquid soap and like materials in which the dispenser consists of a tiltable receptacle, which when tilted in one direction, discharges a certain amount of soap upon the hands of the user and when released swings back to a normal position without shock to the mechanism.

One of the objects of the present invention is to provide a powdered soap dispensing receptacle so formed that it will always swing back when released to its normal position, but may be easily swung to its discharge position with one hand.

A further object is to provide a soap dispenser of such construction that the opening through which the soap is discharged is normally disposed at the top of the dispenser and not at the bottom thereof, thus eliminating any opening at the bottom which would be likely to collect vapor rising from steam or hot water.

A further object is to provide a dispenser of this character with a discharge opening normally covered by a flap valve that opens and closes by means of gravity, this valve when it is closed, preventing water from entering the dispenser, the wall of the opening being so formed as to prevent water from climbing or creeping into the discharge opening.

Another object is to provide means for feeding the soap from the dispenser in a definite regulated quantity upon each operation of the dispenser, this mechanism being so constructed that there are no internal moving parts, springs, levers or the like to get out of order and being so constructed that the amount of soap that it dispenses is regulatable and is capable of being set by the owner of the dispenser and when so set, causes the discharge of a positive and definite quantity of soap upon the hands.

Another object is to provide a soap dis-

penser which has a soap dispensing or measuring unit enclosed within the soap receptacle, which unit can be easily and entirely removed from the dispenser, disassembled and readily cleaned.

Other objects will appear in the course of the following description.

My invention is illustrated in the accompanying drawings, wherein:—

Figure 1 is a side elevation of a soap dispenser constructed in accordance with my invention;

Figure 2 is a top plan view thereof;

Figure 3 is a vertical section from front to rear;

Figure 4 is a transverse section;

Figure 5 is a section on the line 5—5 of Figure 4.

In the drawings I have illustrated a soap dispensing receptacle 10 which has the peculiar form set forth in detail and claimed in my copending application for patent, Serial No. 342,828 filed on the 26th day of February, 1929. This soap dispenser is provided with the lugs 11 at opposite sides having the screw-threaded apertures for the reception of screws 12 passing through bushings 13 in turn carried by a supporting bracket, the arms of which are designated 14. This bracket has a web 15 formed with apertures 75 designed either for the passage of screws or for the passage of U-bolts whereby the bracket can be supported either upon a wall or upon vertical or horizontal pipes. Each of the bracket arms 14 at its bearing end is 70 formed with the downwardly extending stop lug 16 through which a stop screw 17 passes and the body 10 immediately above the bearing lug 11 is provided with the outwardly projecting ears 18 which will strike this stop lug 75 when the body 10 has been fully tilted from its normal position to a discharge position.

The body 10, as more fully detailed in my copending application, has a peculiar form 80

generally speaking, globular and hollow, but what may be termed the outer face of the body 10 is of a flatter curvature than the rear portion of the body. The bearing axis for the body 10 is disposed rearward of a vertical plane normally cutting the middle of the body. The front of the body 10 adjacent its top is formed with the outwardly projecting upwardly curved lip 19. The top of the body 10 is frustrated or cut off on a horizontal plane so as to provide a filling opening 20, there being lugs 21 on each side of the filling opening upon which the top 22 is adapted to be disposed. This top 22 has a flat marginal face which sets against the flat upper edge of the wall or body 10 and two screws 23 pass through the cover or top 22 and into the lugs 21, thus holding the top in place. These screws set down into countersunk openings 20 and preferably are so formed at their outer ends that a small wrench is necessary of a peculiar form in order to remove these screws and permit the removal of the top.

The top is provided at its middle with a pair of outwardly projecting ears 24. The top forward of these ears is provided with a flat seat 25 and a sector-shaped opening 26 disposed adjacent one end of the seat. Coacting with the seat 25 and normally covering this sector-shaped opening 26 is a discharge valve 27 having an ear 28 which extends rearward and is disposed between the ears 24 and pivoted thereto. This valve is normally held by gravity against the seat 25 but as the body is tilted from a normal position to a discharge position and after the body has reached a certain position, this valve will swing open to permit the discharge of a certain amount of soap through the opening 26.

Then as the body swings back to its normal position the valve will, of course, close.

Carried upon the cover or top 22 and preferably made in one piece therewith is the means for measuring out a certain definite quantity of soap to be discharged on each oscillation of the dispensing receptacle. This consists of a tubular web or wall 29 extending downward from the cover or lid 22 and integrally cast therewith. The lower end of this wall is disposed at an angle of approximately 45° as at 30. The wall at one point is formed with a vertically extending opening 31 defined at its lower end by a transverse web 32. On each side of the opening there are formed outwardly projecting ribs 33 rabbeted to form seats for a slide 34 whose function will be later stated.

The interior of the tubular portion 29 is divided by a vertical partition 35 into two chambers 36 and 37. The web 35 is cut away at its lower end as at 38, this opening providing communication at what is the normal lower end of the two chambers 36 and 37. The lower end of the member 29 is closed by a plate 39, held in place by the screws 40 en-

gaging with screw-threaded bores formed in diametrically opposite portions of the wall 29. The upper end of this plate is formed with a slot 41 and beyond the slot the plate is deflected upward as at 42. A screw 43 passes through this deflected end. The lower wall of the slot is disposed at an acute angle to the face of the plate 39 and the upper wall is disposed at a greater angle.

Extending through the slot 41 and bearing against the seats formed in the ribs 33 is the slide 34 previously referred to.

This is a cut-off slide and designed to increase or decrease the effective area of the opening 31. When the slide is pulled downward, the effective area of the opening will be increased and when the slide is pulled upward the effective area of the opening will be decreased. The slide is held in its adjusted position by means of the screw 43.

It will be noted from Figure 4 that the said opening 31 opens into the chamber 37 and this in turn into the chamber 36 and it is the chamber 36 which has the opening 26 normally closed by the valve 27. When the lid is in place and the receptacle 10 is more or less filled with powdered soap, the receptacle will be slightly tilted, that is, a plane extending vertically upward through the centers will not cut through the center of the top 22, or in other words, the seat 20 for this top will not be horizontal, but will be at an angle to the horizontal. Now when the receptacle is fully tilted by depressing the lip 19, the valve 27 will open and any powdered soap which may be within the chamber 36 will be discharged through the opening 26. As the receptacle is tilted to its fully discharging position, the opening 31 or so much of the opening as is left unclosed by the sliding gate 34 will receive soap flowing inward from the receptacle. A predetermined amount of this finely powdered or liquid soap will always flow in to the chamber 37 upon each full tilting movement of the receptacle. Now when the receptacle returns to its normal position which it will do under the action of gravity when pressure is removed from the lip 19, the soap which is within the upper portion of the chamber 37 will drop down upon the inclined plate 30 and will move down by the action of gravity into the chamber 36.

Then when the receptacle is again tilted, this predetermined amount of soap will be discharged through the aperture 26. Thus each time that the receptacle is tilted, a predetermined amount of soap controllable by the effective area of the opening 31 will pass into the chamber 37, then as the receptacle returns to a normal position, it will pass into the chamber 36 and then upon the next succeeding tilting movement, this predetermined amount of soap will be discharged. The amount of soap which will be discharged at

each actuation will depend entirely upon the setting of the slidable gate 32 and thus the amount of soap that is dispensed at each actuation is controllable by the owner of the dispenser.

It will be seen that the globular shape of this soap dispenser will cause it to act as a water shed for all water vapor which may rise from the basin below or other condensation so that this condensed steam or water will collect at the lowest portion of the receptacle and drip off into the basin. It will further be seen that the only opening through which the soap can be discharged is normally closed by the valve 27 so that no water can pass into the top of the receptacle and mingle with the soap.

Furthermore, this opening is defined by a raised rib 25 constituting a seat for the valve and this will additionally prevent any tendency of the water to creep into this opening or pass beneath the valve by capillary attraction.

This soap dispenser has no internal moving parts. The agitation of the soap is secured by the oscillation of the receptacle as a whole and there are no springs, rods, levers, balls or other loose objects which have to be used to stir up the soap. There are no internal moving parts of any kind, no spring, levers or anything of this nature and, therefore, there is nothing to get out of order. The soap dispensing unit comprising the top 22 with the depending tubular member 29, etc., may be removed as a whole from the body 10 so as to permit the body to be filled with soap and so as to permit the soap dispensing unit to be cleaned every now and then.

Preferably the soap dispensing body is mounted for such swinging movement so that the rear side of the body will be presented to the view of the operator when the body is tilted downward and the front side of the dispenser will be presented to the operator when it is in normal position. These front and rear faces are, therefore, preferably provided with advertising matter 26, which may be cast, impressed, or otherwise attached to the receptacle and thus the name of the soap or the name of the manufacturer or other advertising matter may be easily and effectively presented to the user when he is using the device, thus providing a very good method of silent advertising. Preferably, as before remarked, the bracket for the soap dispenser will be so disposed that its arms are in a horizontal position, but I do not wish to be limited to this. The stops will prevent the soap dispenser from being turned so completely around that it will swing into a wrong position.

When released, the soap dispenser will swing back to its normal position without jar or noise and furthermore without any tendency to rack or jar loose the means which sup-

port it. Many soap dispensers are mounted upon plaster walls and tile walls and the strain resulting from their operation or the shock and jar caused by their return or by the soap dispenser striking a fixed stop tends to loosen these parts. This is entirely avoided in my construction because the soap dispenser swings perfectly free upon its pivots or gudgeons and a depression of the soap dispenser to its discharging position merely acts to turn the soap dispenser upon these gudgeons. The return of the soap dispenser to its normal position upon its release is damped by the soap contained within the dispenser whether this soap be liquid or powdered soap so that it does not swing violently back.

Another advantage which is secured by my construction is that there is a perceptible time interval between the discharge of one portion of soap and the discharge of the next portion which tends to prevent wastage of the soap. Where the soap is dispensed by a series of actuations, one following immediately upon the heels of another, there is always waste of soap, but with my device it is necessary that the receptacle shall be allowed to swing back to its normal position before a second portion can be dispensed. This acts to a certain extent as a check upon the user but will not eject more soap than is absolutely necessary.

Economically, this is a very important function which I believe is not found in any other soap dispenser known to me.

While I have illustrated the web or wall 29 as being circular in cross section, I wish it to be understood that this web or wall might be square in cross section without in any way departing from the spirit of the invention and that by the term "tubular" as used in this specification and referring to this wall, I do not wish to limit myself to a circular tube but include a tube of any cross section or contour.

While I have illustrated and prefer to have the receptacle rock or swing in a vertical plane forward and rearward, that is, toward and from the operator, it is obvious that the device might be so set that the receptacle will swing in a vertical plane laterally, that is, in a plane at right angles to the plane in which it is illustrated as rocking without in any way departing from the spirit of the invention.

Furthermore, while I have designed this structure particularly for the purpose of dispensing powdered soaps, it may be equally well used for the purpose of dispensing liquid soaps and it is within the purview of my invention to use it for this purpose.

I claim:

1. A soap dispenser comprising a receptacle mounted for swinging movement in a vertical plane, the top of the receptacle being open, a detachable cover for said open end and having a discharge opening, mechanism

mounted upon the inside face of the cover and disposed entirely within the receptacle acting to discharge a predetermined amount of soap from the receptacle through said opening, as the receptacle is tilted, and a flap valve mounted upon said outer face of the cover and normally closing said opening and swinging to an open position when the receptacle is tilted to discharge position, said opening being defined by a rim, the face of the rim having an outwardly extending flange less in width than the width of the rim and forming a seat for the valve and preventing moisture from entering said opening between the valve and seat.

2. A soap dispenser comprising a receptacle, swingable in a vertical plane, the top of the receptacle being open, a detachable cover for said open end and having a discharge opening, the cover carrying a pair of downwardly extending chambers communicatively connected at their lower ends, the top of one of said chambers being coincident with the outlet opening in the cover and the other chamber having a laterally extending inlet opening adjacent the cover whereby when the receptacle is tilted the material contained in the first named chamber will be discharged and a predetermined amount of material which is within the lowest portion of the receptacle and surrounding the chambers will pass into the second named chamber.

3. A soap dispenser comprising a receptacle swingable in a vertical plane, the top of the receptacle being open, a detachable cover for said open end, the cover being formed upon its inside face with a tubular member extending vertically downward and having a laterally inclined lower end wall, the tubular member being divided by a vertical partition, the partition being cut away at its lower end to provide for communication between said chambers, the longer chamber of the two having a discharge opening extending through the cover and the shorter chamber of the two having a laterally extending inlet opening adjacent the cover whereby material collected at the lower end of the receptacle when the latter is inverted will pass into said inlet opening into said last named chamber.

4. A soap dispenser comprising a receptacle swingable in a vertical plane, the top of the receptacle being open, a detachable cover for said open end, the cover being formed entirely upon its inside face with a tubular member extending vertically downward and having its lower edge laterally inclined, the tubular member being divided by a vertical partition, the partition being cut away at its lower end to provide for communication between said chambers, the longer chamber of the two having a discharge opening extending through the cover and the shorter chamber of the two having an inlet

opening adjacent the cover and opening laterally into the interior of the receptacle, and adjustable means for controlling the effective area of said last named opening, comprising a slide shiftable longitudinally along the opening to reduce or increase its area, and means for holding the slide in adjusted positions.

5. A soap dispenser comprising a receptacle swingable in a vertical plane, the top of said receptacle being open, a detachable cover for said open end, the cover being formed to provide a depending tubular member having an upwardly and laterally inclined lower wall, the tubular member being divided into two chambers by a vertical partition, the lower end of the partition being cut away to provide communication between the two chambers, the longer of the two chambers opening through the wall of the cover, the shorter of the two chambers having an inlet opening in its outside wall, the bottom of the chambers extending beyond said inside wall and being slotted, a slide vertically movable through said slot to reduce or increase the effective area of the opening into said chamber, means for holding the slide in adjusted positions, and a flap valve mounted upon the exterior of the cover and normally closing the discharge opening through the same but swingable to open position when the receptacle is tilted toward its discharge position.

6. A soap dispenser mounted for swinging movement in a vertical plane and approximately globular in shape, the top wall of said receptacle having depending from it an approximately tubular member, the lower edge of which is inclined upward and laterally, the tubular member being divided into two chambers by a vertical partition, terminating short of the bottom whereby to provide communication between the two chambers, the partition extending parallel to the plane of tilting movement of the receptacle, the longer of the two chambers opening through the top of the receptacle, the shorter of the two chambers having an inlet opening adjacent the top of the receptacle, manually adjustable means for regulating the effective area of said inlet opening, and a flap valve mounted upon the exterior of the receptacle and normally closing the outlet opening from the outer chamber, but swingable to open position as the receptacle is tilted.

7. A soap dispenser comprising a receptacle swingable in a vertical plane and having a discharge opening at its top, a tubular member extending vertically downward from the top of the receptacle and having a laterally inclined lower end wall, the member being divided by a vertical partition into two chambers, the partition being cut away at its lower end to provide for communication between said chambers, the longer chamber of the two discharging through the opening in

the receptacle and the shorter chamber of the two having an inlet opening adjacent the top of the receptacle and opening laterally into the interior of the receptacle whereby when the receptacle is inverted, material in the lowest portion of the receptacle will pass through said inlet opening into the interior of the chamber, and adjustable means for controlling the effective area of the last named inlet opening.

10 In testimony whereof I hereunto affix my signature.
